(57) **CLAIM**

The ornamental design for a support platform with ball rollers, as shown and described.

DESCRIPTION

FIG. 1 is a top isometric view of a support platform with ball rollers;

FIG. 2 is a bottom isometric view thereof;

FIG. 3 is a top plan view thereof;

FIG. 4 is a bottom plan view thereof;

FIG. 5 is a right side elevation view thereof, the left side thereof being symmetrical with the right side; and,

FIG. 6 is a front side elevation view thereof, the rear side thereof being symmetrical with the front side.

The broken lines in the drawings depict portions of the support platform with ball rollers that form no part of the claimed design.
